UNITED STATES PATENT OFFICE.

TEODORO LARREY AND LUIS GODARD, OF MEXICO, MEXICO.

BOILER CONSTRUCTION.

Application filed July 9, 1919. Serial No. 309,550.

To all whom it may concern:

Be it known that we, TEODORO LARREY and LUIS GODARD, citizens of the United Mexican States, residing at Mexico city, Federal District, Mexico, have invented certain new and useful Improvements in Boiler Constructions, of which the following is a specification.

This invention relates to locomotive boilers and to stationary and marine boilers; and its object is to utilize the initial heat in the fire-box, by increasing the heating surface and by spreading the flames in its interior, which is effected by means of a shallow drum disposed a certain distance from, and opposite to, the entry of the flues into the fire-box.

The invention further resides in utilizing the above-mentioned drum in such a way as to obtain a better circulation of the water in the boiler, the drum serving, by reason of its position in the interior of the fire-box, to heat the water more rapidly and cause it to rise more quickly.

Another object of the invention is to provide a deflector in the smoke-box opposite to the ends of the flues, so that, by means of the forced draft, the flames, gases and smoke will be drawn through the flues in a more uniformly distributed manner and the hot gases, on escaping around the edges of the deflector, will be caused to envelop the steam pipes, whereby they again heat the steam with the result that dry, super-heated steam is taken into the cylinders.

In the accompanying drawings:

Fig. 1 is a broken, side elevation of a locomotive smoke-box constructed in accordance with the invention.

Fig. 2 is an enlarged vertical cross-section of the smoke-box and stack.

Fig. 3 is a fragmental side elevation of the rear end of the locomotive, with parts removed to show the water-circulating drum in the fire-box.

Fig. 4 is an elevation of part of the fire-box, showing the water-circulating drum and the ends of the flues.

Referring more particularly to the drawings, 1 is the shell of the boiler, the smoke-box 2 of which has disposed within it an exhaust pipe 3, which receives the exhaust stem from the exhaust ports of the cylinders (not shown) and which is provided with a coupling flange 4. Flange 4 is coupled to the flange 5 of the exhaust nozzle 6, within

which latter there is suspended a bell 7 having a flange 8 which is coupled by means of bolts 9 to a flange 10 formed on the lower end of a pipe or tube 11. The upper end of this pipe 11 is provided with two diverging branches 12, which are connected to horizontal pipes 13, the latter delivering the exhaust steam to the impact condenser (not shown).

The exhaust pipe 3 is provided in its interior with a bridge 29 having a vertical guide opening for the stem 30 of a valve 31, which is shaped like a buoy and which, on being raised, engages in bell 7. Said bell 7 thus serves as a valve seat and in this way enables the steam passage to be closed. The lower end of stem 30 is linked at 32, (see Fig. 1) to a lever 33 mounted on a horizontal rock-shaft 34 having an arm 35 connected thereto. The other end of this arm 35 is pivoted to a rod 36 which extends along the outside of the boiler to the engineer's cab, so that by pushing or pulling this rod 36 the engineer may lower or raise valve 31 at will.

When valve 31 is raised and seated in bell 7, the passage of steam to the condensers is closed, and all of the exhaust steam will then escape through an annular opening 37 provided between bell 7 and the mouth of the exhaust nozzle 6, and will enter the collector 38 of smoke stack 39, whence it passes into the atmosphere.

In the smoke-box 2, and opposite the flue-plate 40, (Fig. 2) there is arranged a concavo-convex deflecting plate 41, provided with reinforcements or webs 42, said plate being suspended vertically in the smoke-box by means of brackets 43, with its concave face opposite and in spaced relation to the flue 95 plate, and its marginal edges spaced continuously from the circumferential walls of the smoke-box. The marginal outline of the deflector parallels that formed by the peripheral tubes in the flue-plate 40 and lies in immediate proximity to the said tube outline; and due to that fact, it serves the purpose of causing the draft to draw the smoke, hot gases and flames from the fire-box in such a manner that they will pass around the 105 edges of the deflector in proportion to each flue 44 and will also envelop the steam pipes connecting the boiler and cylinders (not shown).

Figs. 3 and 4 show the fire-box 47 equipped with a heating drum 48 for effecting a better circulation of the water. This

drum communicates through pipe 49 with crown sheet 50, and through pipes 51 with the lateral water spaces. It is provided with the necessary stay-bolts or braces 52 5 and, as may be seen, is suspended vertically in the fire-box opposite the entry of the flues, so that it compels the flames to spread inside the fire-box; and since the heat in the 10 interior of the fire-box is greater than in the flues, it follows that the water in the drum 48 will be heated more rapidly and a better circulation of water in the boiler will be maintained than is the case at present.

Drain plugs 53 are provided in the shell 15 of the boiler to permit the drum 48 to be cleaned.

Having thus described our invention what we claim is:

1. In a boiler operating under forced 20 draft, the combination, with the smoke stack, the front and rear flue plates and their connecting flues; of a chamber immediately adjacent each flue plate and in which flames, hot gases and smoke are present; 25 and a combined draft equalizer and products of combustion deflector consisting solely of an imperforate deflecting element of less area than the adjacent flue plate suspended vertically in one of said chambers 30 in rear of the smoke stack opposite and in spaced relation to the flue openings and with its margin continuously spaced from the circumferential walls of said chamber so as to cause the flames, hot gases and 35 smoke to be drawn by the forced draft around the marginal edges of said deflecting element in a uniform manner; substantially as described.

2. In a boiler operating under forced 40 draft, the combination, with the smoke stack, the smoke-box and fire-box and the front and rear flue plates and their connecting flues, of a combined draft equalizer and

products of combustion deflector consisting solely of an imperforate deflector plate of 45 less area than the front flue plate disposed vertically within the smoke-box in rear of the smoke stack but in front of, and in spaced relation to, said front flue plate, and a series of brackets mounted in the smoke-box for suspending the deflector plate therein with its marginal edges spaced from the circumferential walls thereof, so as to cause the forced draft in the smoke-box to draw the flames, hot gases and smoke from the 50 fire-box through said flues and around the said marginal edges of the deflector plate in a uniformly distributed manner.

3. In a boiler operating under forced 55 draft, the combination of a smoke box; flue tubes passing through the boiler and terminating at their forward ends at a tube sheet in the smoke box; and a single element acting as a combined draft equalizer and products of combustion deflector disposed vertically in the smoke box adjacent the tube sheet and having a marginal outline which parallels that formed by the peripheral tubes in the tube sheet and which lies in immediate proximity to the said tube 60 outline, whereby the area of the surface of the deflector confronting said tubes is substantially equal to the area of the tube zone of the tube sheet, said deflector being so arranged with relation to the tube sheet that 65 the products of combustion are caused by the forced draft to pass over the entire confronting surface of the deflector in a radial direction and around the marginal edges thereof, and so that the forced draft in each 70 flue tube is substantially equal to the draft in each of the other flue tubes.

In testimony whereof we have affixed our signatures.

TEODORO LARREY.
LUIS GODARD.
